UNITED STATES PATENT OFFICE.

WILLIAM B. SMITH, OF ATLANTA, GEORGIA.

COTTON-HOE.

SPECIFICATION forming part of Letters Patent No. 461,133, dated October 13, 1891.

Application filed March 20, 1891. Serial No. 385,740. (No model.)

To all whom it may concern:

Be it known that I, WILLIAM B. SMITH, of Atlanta, in the county of Fulton and State of Georgia, have invented a new and useful Im-

5 provement in Cotton-Hoes, of which the following is a specification.

My invention relates to an improvement in cotton-hoes in which a disk-fender acting as a traction-wheel actuates a thinner or cutter 10 transversely to the row or path in which the plow travels, the traction-disk and thinner or cutter forming an attachment for plows of ordinary structure.

A practical embodiment of my invention is 15 presented in the accompanying drawings, in which—

Figure 1 is a view of the plow in side elevation with the attachment secured thereto as in use. Fig. 2 is a top plan view of the same. 20 Fig. 3 is a horizontal section through line xx of Fig. 1. Fig. 4 is an enlarged sectional view of the joint at the plow-beam. Fig. 5 is a view in detail of one form of thinning or cutting disk, and Fig. 6 is a view in detail of another 25 form of thinning or cutting disk.

A represents a plow-beam, to which a plow a , of any ordinary or desired form, may be attached.

To one side of the beam A one member B 30 of the attachment connection is secured and is provided on its lower face with a rounded projection b , adapted to seat in the concave face b' of the other member B' of the connection. The lower face of the member B' is 35 provided with a recess b^2 for the reception of the upper end of the hanger C, to which the operating parts of the attachment are secured. The faces of the projection b and seat b' are roughened to prevent slipping, and a bolt extending through the hanger C and the members B and B' serves to lock the parts in the 40 desired adjustment. It is obvious that the concave seat might be made in the member B and the rounded projection on the member B'.

The combined traction disk and fender D is 45 made dish-shaped, and is intended to present its convex side toward the row when in operation. Its edge is notched to afford it a better 50 hold upon the earth in proximity to the row, and it is provided upon its outer face with

an annular series of teeth d , adapted to engage and rotate a pinion e , secured in a shaft E, as will hereinafter be more particularly referred to.

55

The hub d' of the traction-disk is provided with a taper bore adapted to fit a taper spindle F. The spindle F has a bore f extending longitudinally therethrough, and has a concave seat f' on its inner end. The spindle is secured to the hanger by means of an L-shaped extension f^2 , formed integral with or fixed to the spindle at one end, and at its opposite end provided with an attachment precisely similar to that shown by the parts B B', the 60 part corresponding to B' being provided with a recess f^3 , in which the lower end of the hanger is secured.

65

A horizontal frame G, having a general U-shaped form, extends from the inner end of 70 the spindle around the edge of the traction-disk and back to the outer end of the spindle. The said frame G is provided at the inner end of the spindle with a rounded projection g , adapted to engage the concave seat f' in the 75 end of the spindle and is provided along its outer branch with a bearing g' for the reception of the operating-shaft E carrying the pinion e . The portion g^2 of the frame G which extends from the bearing g' to the outer end 80 of the spindle preferably extends up and over the pinion e , as shown in Fig. 1. The ends of the frame G are secured to the spindle and the traction-disk is secured on the spindle by means of a bolt H, which extends through the 85 spindle and through both ends of the frame.

The direction of the shaft E is such that the cultivator-disk which it carries upon its rear end occupies a position substantially transverse to the row or the path in which the 90 plow travels. The cultivator-disk may be either a series of arms i radiating from a hub I, as shown in Fig. 5, or it may consist of a curved blade i' extending partially around the periphery of the disk and secured to the 95 hub I' by arms i^2 , as shown in Fig. 6. In either case the disk is removably secured to a hub e' fixed on the end of the shaft E, the adjacent faces of the hubs I I', and the hub e' on the shaft being roughened or serrated 100 to prevent slipping. The face of the hub e' may be provided with screw-threaded studs

e^2 , adapted to enter perforations i^2 in the hubs $I I'$ for holding the cultivator-disks in the desired adjustment.

The traction-disk D may be set at any desired angle to the row by the adjustment of the spindle F relatively to the hanger C by means of the connection at f^2 on their supports, and the whole attachment may be adjusted toward and away from the plow-foot

10 by means of the connection at the beam.

The rotary movement of the traction-disk as the plow advances rotates the cultivator-disk either a thinner or a cutter, and the arms i or blade i' will cut across the row at intervals, depending upon the number of arms i or the interval between the ends of the cutting-blade i' . The latter having a cutting-edge on the front of its rim will alternately cut with a shearing cut, and then skip as the

20 plow advances.

What I claim is—

1. In a cotton-hoe, a traction-disk and means

for attaching it to a plow or the like, a frame secured to and carried by the spindle of the traction-disk, and a cultivator-disk 25 mounted in the frame and geared to the traction-disk, the cultivator-disk having a rotary movement in a plane transverse to the path of the traction-disk and having its cultivating-blade arranged to act at intervals, substantially as set forth.

2. In a cotton-hoe, the adjustable hanger, the adjustable frame and spindle secured to the hanger, the combined fender and traction disk mounted on the spindle and having 35 an annular gear on its face, a shaft journaled in the frame and having a pinion adapted to gear with the annular gear, and a cultivator-disk removably secured to the shaft, substantially as set forth.

WILLIAM B. SMITH.
